UNITED STATES PATENT OFFICE.

DANIEL T. WHITE, OF RACINE, WISCONSIN.

LUNCH-BOX.

1,115,635.

Specification of Letters Patent.

Patented Nov. 3, 1914.

Application filed September 25, 1913. Serial No. 791,870.

To all whom it may concern:

Be it known that I, DANIEL T. WHITE, a citizen of the United States, residing at Racine, in the county of Racine and State 5 of Wisconsin, have invented a new and useful Lunch-Box, of which the following is a specification.

This invention relates to improvements in dinner-pails.

10 An object of the present invention is to provide a dinner pail with two partitions extending longitudinally thereof spaced a slight distance from the side walls of the dinner pail and forming liquid receiving 15 reservoirs for the reception of tea, coffee, or like substance and which may be heated by means of a lamp disposed beneath the bottom plates of the reservoirs.

20 A further object is to provide a dinner pail of novel form and to improve and simplify the construction thereof whereby it may act as a carrier for the various articles constituting a meal, including one or two different liquids and to provide 25 means whereby the latter may be conveniently and readily heated.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 35 within the scope of what is claimed, without departing from the spirit of the invention.

In the drawings accompanying this specification and forming a part thereof, the preferable form of my invention is illustrated, in which:—

40 Figure 1 is a view in perspective of my improved dinner pail. Fig. 2 is a cross sectional view thereof taken on the line 2—2 of Fig. 1. Fig. 3 is a view in elevation 45 of one of the heating lamps.

Referring to the drawings in which similar reference numerals designate corresponding parts throughout the several views, 4—4 are the side walls, and 5 and 50 6 the front and rear walls to which is secured the bottom 7.

Spaced a slight distance from and extending parallel to the side walls 4—4 are the vertical partitions 8—8 which are provided with the inwardly extending flanges

9 at their lower extremities which rest flat upon the inner surface of the bottom 7 and are soldered or secured in a liquid-tight manner thereto by some equivalent means. The upper extremities of the partitions 8 60 are bent sharply inwardly to form the top of a liquid receiving compartment as at 10 at which location they contact with the inner surfaces of the side walls 4 and extend upwardly and contact therewith as at 65 11. The upper extremities of the side walls 4—4 are bent upon themselves as at 12 and also embrace the upstanding flanges 11 therebetween to hold the same rigidly in place and effecting a liquid-tight joint therewith. A plate 13 is provided with downwardly extending flanges 14 and which is positioned between the walls 4 and partitions 8 and forms the bottom of the liquid receiving compartments 15. The end walls 75 of the compartments are provided by the end walls 5 and 6 of the dinner pail with which the partitions 8 contact and are soldered or held thereto. Thus it will be apparent that the provision of the partitions 80 8 and bottom plate 13 define two liquid receiving compartments the outer walls of which are formed by the outer walls of the dinner pail and which are adapted to receive a liquid therein such as coffee, tea, 85 or allied substance which may be poured therein through the spouts 16 which may be closed by the corks 17 and which also provides a delivery outlet through which the liquid may be emptied, it being noted in 90 this connection that a suitable air inlet opening 18 is provided to facilitate the filling and emptying of the liquid receiving compartment.

The front end wall 5 is provided with the 95 openings 19 therein and which provide entrance for the lamp receiving compartment disposed beneath the reservoirs or liquid receiving chambers 15. The provision of the bottom plate 13 for the liquid receiving 100 compartments 15 provides a top for the lamp receiving compartments 20 which extend the entire longitudinal distance of the dinner pail and are cut off from the interior thereof by reason of the fact that the partitions 8 extend through and are rigidly secured to the bottom plate 7 of the dinner pail. In order to provide for the proper amount of air for the burning of the lamps within the lamp compartments 20 the side 105 110

walls 4—4 are provided with a plurality of slots 21 and apertures 22 allowing for the entrance and exit of air and providing for the proper burning of the lamps. The edges 5 23—23 of the dinner pail are provided with an outstanding tongue 24 slidably engaging with which is the curled portion 25 of the sliding door 26. The sliding door 26 is provided with a finger engaging lip 27 for the 10 proper and convenient manipulation thereof. The door 26 is of a width sufficient to completely close the entrance 19 to the lamp receiving chambers so that when the door is in a lowered position the lamps will be held 15 and completely housed by the lamp receiving compartments and will be held against being accidentally displaced or lost therefrom.

A lamp is illustrated in Fig. 3 and comprises a fuel reservoir 28 with a handle 29 projecting therefrom, the combined length of the handle and reservoir being just sufficient to fit within and be housed by the lamp receiving compartment 20 and which when 25 the sliding door 26 is closed thereupon will be prevented from longitudinal movement which would produce more or less unpleasant rattling. A wick tube 30 communicates with the reservoir 28 and in which 30 extends a wick 31 which when lighted and in position within the lamp receiving compartment 20 will properly heat the liquid disposed within the liquid receiving compartment 15 beneath which it is centrally disposed. In order to prevent undue evaporation of the fuel which in most cases will be alcohol or some similar fuel, a wick protecting cap 32 is provided and completely houses the wick during the non-use of the 35 lamp. A fuel inlet 33 is provided and is closed by a cap 34, the same providing means for supplying the lamp with fuel. It will be noted that there will be two of the foregoing described lamps used in connection with each dinner pail as there are two of the liquid receiving compartments 15 in which the liquids may be inserted.

The ends walls 5 and 6 are provided with upstanding holding members 35 provided 50 with suitable apertures 36 extending therethrough and in which is placed the bail 37 whereby the dinner pail may be conveniently carried. A cup 38 is frictionally secured to the upper lid 39 and is of the usual 55 construction. The lid 39 which is adapted to form a closure for the interior of the pail comprises the top plate 40 and the downwardly extending rim 41 which fits within the curled or rim portion 12 of the side and 60 end walls with which it is adapted to contact and frictionally engage. The partitions 8 are provided with a plurality of angle members 42 which are adapted to support a tray 43, the latter being provided 65 with upstanding flanges 44 for the suitable

retention of any articles which may be positioned thereupon. The tray is also provided with the inwardly and upwardly extending members 45 whereby the tray may be conveniently lifted from the interior of 70 the pail.

From the foregoing it will be apparent that the entire pail is of simple design and yet able to carry various articles therein and also provides means whereby liquids may be 75 carried and heated.

Having thus fully described my invention, what I claim as new is:

1. A dinner pail comprising side and end walls with a bottom secured thereto, partitions spaced a slight distance from and extending parallel to the side walls thereof, transversely extending plates extending between the partitions and the adjacent side walls and defining liquid receiving and lamp 85 receiving compartments, said walls provided with a plurality of openings extending therethrough adjacent the lamp receiving compartments for the entrance and exit of air, one of the said end walls provided with 90 openings extending therethrough defining entrances communicating with the lamp receiving compartments, and means slidably secured to the said end wall for the closing of the said entrance. 95

2. A device of the character described comprising a pail, a lid therefor, partitions extending parallel to and spaced a slight distance from the side walls thereof stopping short of the top of the side walls, said partitions bent sharply inward at the top to contact with the inner surface of the side walls and rigidly secured thereto, bottom plates extending between the said partitions and adjacent side walls and defining the bottom wall of a liquid receiving compartment and the top wall of a lamp receiving compartment respectively, the front end wall of said pail provided with openings extending therethrough and forming entrances for the lamp receiving compartments, a sliding door with a finger engaging portion offset therefrom adapted to close the said entrance to prevent the accidental displacement of the lamps from the lamp receiving compartments, the side walls of the pail adjacent the lamp receiving compartment provided with a plurality of openings extending therethrough for the entrance and exit of air for the proper burning of the lamps, and a lamp 105 insertible within the said lamp receiving compartments for the heating of the liquid within the said liquid receiving compartments. 110

3. In a dinner pail the combination of a 115 body portion with the upper edges thereof bent to form a downwardly extending rim, partitions extending parallel to and spaced a short distance from the side walls provided at their lower extremities with offset 120 flanges. 125

flanges contacting with the bottom of the body portion, the upper extremities of the partitions stopping short of the upper extremities of the side walls and bent inward 5 to form the top of a liquid receiving compartment, the said top extending to and contacting with the inner surface of the side wall and projecting beneath the downwardly extending rim thereof to effect a tight junction therewith, plates extending between the partitions and adjacent side walls and defining the bottom of a liquid receiving compartment and the top of a lamp receiving compartment respectively, lamps insertible 10 within the said lamp receiving compartments and adapted to heat the said liquid receiving compartments disposed thereabove,

the front end wall of the body portion provided with openings extending therethrough and defining lamp compartment entrances, 20 the edges of the said end wall provided with outstanding tongues, a sliding door provided with interlocking edges slidably engaging the said tongues and adapted to close the lamp receiving compartment entrances, and a lid for the body portion. 25

In testimony that I claim the foregoing as my own, I have hereto affixed my signature in the presence of two witnesses.

DANIEL T. WHITE.
